DESIGN FOR A SHAVING BOWL

Jules B. Montenier, Chicago, Ill.

Application March 10, 1945, Serial No. 118,399

Term of patent 14 years

(Cl. D86—10)

To all whom it may concern:

Be it known that I, Jules B. Montenier, a citizen of the United States, residing at Chicago, in the county of Cook and State of Illinois, have invented a new, original, and ornamental Design for a Shaving Bowl, of which the following is a specification, reference being had to the accompanying drawing, forming a part thereof.

In the drawing:

Fig. 1 is a front elevational view of a shaving bowl showing my new design.

Fig. 2 is a side elevational view thereof, and
Fig. 3 is a plan view thereof.

I claim:

The ornamental design for a shaving bowl, substantially as shown.

JULES B. MONTENIER.
